CLAIM

The ornamental design for a bioelectrochemical reactor, as shown and described.

DESCRIPTION

FIG. 1 is a front perspective view of a bioelectrochemical reactor showing our new design, shown in an environment of use;

FIG. 2 is a side view of the bioelectrochemical reactor of FIG. 1;

FIG. 3 is a side view of the bioelectrochemical reactor of FIG. 1 opposite the side view shown in FIG. 2;

FIG. 4 is an end view of the bioelectrochemical reactor of FIG. 1;

FIG. 5 is an end view of the bioelectrochemical reactor of FIG. 1 opposite the end view shown in FIG. 4;

FIG. 6 is a top view of the bioelectrochemical reactor of FIG. 1;

FIG. 7 is a bottom view of the bioelectrochemical reactor of FIG. 1;

FIG. 8 is an exploded perspective view of the bioelectrochemical reactor of FIG. 1;

FIG. 9 is a front perspective view of bioelectrochemical reactor, shown with the environmental subject matter removed;

FIG. 10 is a side view of the bioelectrochemical reactor of FIG. 9;

FIG. 11 is a side view of the bioelectrochemical reactor of FIG. 9 opposite the side view shown in FIG. 10;

FIG. 12 is an end view of the bioelectrochemical reactor of FIG. 9;

FIG. 13 is an end view of the bioelectrochemical reactor of FIG. 9 opposite the end view shown in FIG. 12;

FIG. 14 is a top view of the bioelectrochemical reactor of FIG. 9; and,

FIG. 15 is a bottom view of the bioelectrochemical reactor of FIG. 9.

The broken lines in the FIGS. 1-8 represent environmental subject matter which forms no part of the claimed design.

(Continued)

The broken lines in FIGS. 9-15 represent portions of the article which for no part of the claimed design.
